UNITED STATES PATENT OFFICE.

EDWIN CLARK, OF CHICAGO, ILLINOIS.

CORN HUSKER.

Application filed April 29, 1922. Serial No. 557,413.

To all whom it may concern:

Be it known that I, EDWIN CLARK, a citizen of the United States, residing at Chicago, in the county of Cook and State of Illinois, have invented certain new and useful Improvements in Corn Huskers, of which the following is a specification.

This invention relates to improvements in tools of the class now generally known as corn husking pins.

One object of the invention is to provide an improved tool of this character having means whereby the grip or handle portion may be readily and positively adjusted to various sizes. Another object is to provide a tubular hand grip in a tool of this class and a further object is to provide an improved device which will be self supporting upon the hand of the husker entirely independently and free of all straps, gloves and other apparatus of a similar nature such as are commonly used in attaching or holding such tools to the hand.

Other objects and advantages will be apparent from the following specification, taken in connection with the accompanying drawings, wherein one form of the invention is illustrated.

In the drawings—

Figure 1 is a plan view of a husking pin constructed in accordance with the present invention;

Fig. 2 is a side elevation of the pin, partly in section;

Fig. 3 is a sectional view, taken on the line 3—3 of Fig. 2;

Fig. 4 is a sectional view, also taken on the line 3—3 of Fig. 2, but showing the movable portion of the handle in position to be adjusted;

Fig. 5 is a rear elevation of the tool; and

Fig. 6 is a fragmentary side elevation of modification.

Referring more particularly to the drawings, the husking pin is shown of sheet metal construction, and comprises the rolled longitudinally extending staff or handle element 10, the latter terminating at one end in an outwardly and laterally projecting husking finger 11, and an outwardly and downwardly curved guard 12. Carried on the

handle portion, and longitudinally adjustable thereon, when in a certain position, is a second guard 13, the latter terminating at its inner end in a elongated sleeve or collar 55 13^a circumferentially corrugated, as at 13^b. The handle portion 10 passes through the sleeve 13^a, the latter together with the guard being longitudinally adjustable upon said portion. The longitudinal edges of the 60 sleeve are spaced apart, as shown in the drawings, in order to provide for the passage therebetween of a plurality of bosses or lugs 10^a struck upon one side of the handle portion. 65

In assembling the two parts of the tool the guard 13 is slipped over the outer end of the handle portion 10 and moved inwardly thereon, so that the lugs 10^a are received between the edges of the sleeve. The guard is 70 then turned a half revolution upon the handle portion, during which the bosses engage the corrugations 13^b and serve to hold the guard against longitudinal displacement, except that a slight longitudinal movement is 75 permitted at the end of said half turn to lock the two members against rotation. This locking is preferably effected by a small recess 13^c communicating with each of the annular grooves 13^b. The slight longitudinal 80 movement referred to draws the bosses or lugs 10^a into said recess 13^c, thereby preventing relative rotation of the two parts. This locking against relative rotation may be accomplished in various other ways. For 85 example, the recess might be replaced by holes in the sleeve or holes might be provided both in the handle 10 and the sleeve, through which a small pin might be inserted. A further alternative would be indentation, 90 holes or notches in either the handle or the sleeve and struckup lugs in the other part so that one might snap into the other and resist turning when in use, the parts being disengaged by twisting them with sufficient 95 pressure, which pressure would not be applied when the husker was in use. A further alternative is the provision of a wire, parts of which would engage the slit in the tubular member and other parts engage the spaced 100 apart edges of the sleeve, thereby locking against rotation.

As will be appreciated, the

2
guard may be adjusted at any time by merely sliding the two parts toward each other a fraction of an inch, and rotating one of them half a revolution in order to disengage 5 the sleeve from the lugs or bosses, thus leaving the guard free to be moved in either direction along the tubular portion until the desired position of adjustment has been reached, at which time a half revolution of 10 the guard upon the tubular portion and a slight longitudinal pull serves to lock the same again in its adjusted position and against displacement.

The construction shown in part in Fig. 6 15 is the same as that shown in Figs. 1 and 2, except that the recesses 13^a are omitted. It is preferred in practice to construct the lugs or bosses 10^a of such size that they engage the corrugations 13^b with considerable friction, 20 so that the guard in its various positions of adjustment will be substantially rigid.

As will be observed from the drawings the front guard 12 curves outwardly and rearwardly from the pin, while the rear 25 guard 13 curves outwardly and forwardly therefrom. These guards, as will be appreciated, are designed to receive the hand of the operator and, by reason of their configuration, serve to support the pin on the 30 hand, even though the latter should be open. In other words, no actual gripping of the device is necessary to maintain the same in operative position. In the form of device 35 shown in Fig. 6, the two parts may rotate on each other slightly when the device is being used without danger of their becoming disengaged and pulling apart longitudinally. In practice the guards are relatively 40 adjusted to accommodate the hand of the husker, and so that when applied to the hand the pin will be held transversely there- 45 of along substantially the line defined by the bases of the fingers. If desired, each guard may be apertured adjacent its outer end, as shown at 12^a and 13^a respectively, 50 so that a lacing of some sort may be em- 55 ployed across the ends of the guards as a further precaution against displacement of the pin while in use. A further feature 60 is the provision of the cutting edge or notch 13^b in either side of the guard 13. The edge is protected from accidental contact 65 with other objects by the restricted mouth of the notch. The usefulness of this cutting edge will readily suggest itself to those skilled in the art.

Although I have shown and described my invention as being embodied in certain preferred forms, it will be understood that I do 70 not desire to be limited thereto unduly. On the contrary, I contemplate all proper changes in form, construction, and arrangement, the omission of immaterial parts, and the substitution of equivalents, as circum-

stances may suggest or necessity render expedient.

I claim—

1. A tool of the class described comprising a tubular handle portion, a husking point, an outwardly and rearwardly curved 70 guard, all of integral sheet metal construction, and a second guard rotatably and adjustably mounted on said handle portion.

2. A tool of the class described comprising a handle portion, a husking point, an outwardly and rearwardly curved guard, a second guard carried by said handle portion, and means whereby the same may be adjusted longitudinally and laterally thereof.

3. A tool of the class described comprising a handle portion, a husking point, an outwardly and rearwardly curved guard, a second guard carried by said handle portion, said guard terminating in a corrugated sleeve at its inner end, said sleeve adjustably engaging said handle portion, and means carried by said handle portion for engaging the corrugations of said sleeve to prevent displacement.

4. A tool of the class described comprising a handle portion, a husking point, an outwardly and rearwardly curved guard, a second guard carried by said handle portion, said guard terminating in a corrugated sleeve at its inner end, said sleeve adjustably engaging said handle portion, means carried by said handle portion for engaging the corrugations of said sleeve to prevent displacement, said guard being capable of longitudinal adjustment with respect to said handle portion upon rotation of said sleeve a fraction of a revolution.

5. A tool of the class described comprising a tubular handle portion, a husking point, and a plurality of outwardly curved 105 guards for engagement with the hand of the husker for holding the tool in operative position thereon, one of said guards being adjustable both longitudinally and laterally with respect to the other.

6. A tool of the class described comprising a tubular handle portion, a husking point, a plurality of outwardly curved guards for engagement with the hand of the husker for holding the tool in operative 115 position thereon, and means associated with one of said guards to permit adjustment of the same upon relative rotation of said last named guard and handle portion.

7. A husking pin comprising a handle portion a guard, a husking point at one end thereof and a second guard rotatably mounted on said handle portion adjacent the other end thereof.

8. A husking pin comprising a handle portion, a husking point and a guard rotatably mounted on said handle portion, the mounting of said guard being such that the same

may be adjusted both laterally and longitudinally to accommodate the hand of the husker.

9. A husking pin comprising a handle portion, a husking point, a guard rotatably mounted for lateral adjustment on said handle portion and means whereby said guard may be adjusted longitudinally of said han-

dle portion upon rotation of the former to a predetermined position with relation to the latter, said guard being automatically locked against longitudinal movement upon return thereof.

In testimony whereof, I have subscribed my name.

EDWIN CLARK.
